UNITED STATES PATENT OFFICE.

JOHN S. PARKE, OF UNITED STATES ARMY.

RAPID-TRANSIT APPARATUS.

SPECIFICATION forming part of Letters Patent No. 443,972, dated December 30, 1890.

Application filed July 8, 1890. Serial No. 357,696. (No model.)

To all whom it may concern:

Be it known that I, JOHN S. PARKE, United States Army, stationed at Fort Sidney, in the State of Nebraska, have invented a new and 5 useful Improvement in Rapid-Transit Apparatus, of which the following is a specification.

My invention is an improved rapid-transit apparatus, and has for an object to provide a 10 novel construction enabling the running of carriages or trains at great speed. I propose to attain great speed by utilizing the explosive force of gunpowder or some analogous substance which is capable of sudden conversion into an expansive gas.

The invention consists in certain features of construction and novel combinations of parts, as will be hereinafter described, and pointed out in the claims.

20 In the accompanying drawings, which illustrate one method of carrying out the invention, similar letters refer to similar parts throughout.

Figure 1 is a side elevation of my improved 25 apparatus. Fig. 2 is a side elevation of a portion of the track. Fig. 3 is a cross-section of the track. Fig. 4 is a longitudinal section of a part of the track. Fig. 5 is a detail view of one of the rack-plates. Fig. 6 is a longitudinal section of the locomotive. Figs. 7, 8, and 9 are detail views of parts thereof. Fig. 10 is a longitudinal section of the passenger 30 or freight car. Fig. 11 is a rear end view thereof. Figs. 12 and 13 are cross-sections on respectively lines 12 and 13 of Fig. 10. Fig. 14 is a side view of a part of the track, locomotive, and connecting-frame. Fig. 15 is a cross-section of the connecting-frame, and Fig. 16 is a detail view of the piston.

40 My improved apparatus includes the construction of the track with a ratchet or rack, the locomotive or power-car to run on said track and having a piston engaging the rack of the said track and the cannon-like device 45 for operating said piston, the car for freight or passengers, and the frame connecting said car with the locomotive.

The track A is formed, as shown most 50 clearly in the detail views, with the cross-ties B, the main rails C, the side stringers C', sup-

porting said rails C, the central beam or stringer D, and the intermediate stringers E, arranged on opposite sides of the beam D.

The beams C', D, and E are supported upon and anchored to the ties B, and said beams 55 are also connected and braced laterally by tie-rods F, extended through them and secured at the outer sides of stringers C', preferably by nuts, as shown, collars or spacing-sleeves f being supported on said tie-rods between the adjacent beams to hold the latter 60 properly apart. I also connect the beams E D E near their lower sides by tie-rods F', collars f' being arranged on the rods between the said beams. 65

The beam D is channeled or otherwise suitably formed at its upper side to receive the rack G, which is preferably formed of similar steel or other suitable plates H, and india-rubber or other suitable cushioning-plates I, 70 arranged at the lower ends of the plates H, as shown, so as to cushion the said plates against the stroke of the driving piston-rod presently described. About midway between their ends the plates H are provided with side 75 flanges h, which bear, in the uppermost position of the said plates, under plates J, which are secured upon stringers E and lap over the beam D. These plates J also form rails for the supporting-wheels of the driving piston-rod. 80

The rails C are formed to receive the runner portions of the locomotive, car or cars, and connecting-frame, and may be flanged, as shown at the right in Fig. 3, or may be of the 85 ordinary form shown at the left of said Fig. 3, so that in applying the improvements to ordinary railroads it will only be necessary to put in the central beams.

To offer less resistance to the air the carriages, in which generic term the "cars" and so-called "locomotive" may be included, are given the shape shown, known as the "cylindro-conoidal," and such carriages have runners 90 39 to slide on rails C.

The locomotive K is formed with suitable framing and casing and is provided with the cannons or guns 1—say six in number—which are fixed to plates 2 3, supported to revolve on or with the axial shaft 4, held by the dia- 100

phragm or division-plates 5 and 6, the cannons being arranged to incline downward toward their muzzle ends.

At their butt-ends or breeches the cannons 5 are held closely against a steel plate 7, and a rod or beam 8 bears between the front side of plate 7 and the framing. This rod 8 is arranged in prolongation of the line of fire through the cannon adjusted to firing position—that is, the lowest position to which the cannons are successively moved as the group of cannons is turned. An opening 9 is formed in plate 7 near its top, such opening serving to admit the cartridge, of which a supply is 15 kept in a trough 10, arranged in line, or approximately so, with the opening 9, so that the cartridges may be conveniently fed into the cannons or barrels as they are successively presented to the opening 9.

20 By using bags or some other combustible material for inclosing the explosive unloading will not be necessary, as it would be if metal cartridges were used; but even if metal cartridges were necessary or desirable, any 25 simple convenient retracting mechanism may be employed.

The operator may sit in a chair 11, supported to slide back and forth on upper and lower rods 12 and 13. The plate 3 has sockets 14 to receive a stop-pin 15, which stops the group of cannons or barrels in operation, and is released by connection with the seat 11. A grooved or notched cap 16 is adapted to fit on the barrels, and is supported to drop 35 down on the uppermost cannon and stop or steady the same in position to hold the plate 3 in position for its socket 14 to receive pin 15, sockets 14 being provided one for each barrel. I support this cap 16 by an arm or 40 bar extended from it to and connected with the side of the locomotive-frame, and I operate the cap by means of a cord 17, which extends over a pulley 18, and is connected with the operator's chair, so that the recoil 45 of the operator's chair after a shot is fired will release the cap 16 and pin 15, when the bunch of guns will be turned sufficiently to bring the next pair thereof into position for firing and loading. After a shot is fired the 50 pin 15 will be withdrawn and the cap 16 raised by the movement of the operator's chair, and the movement of the chair will also turn the group of guns one space by means of the ratchet-and-pawl mechanism, as shown, 55 which mechanism may obviously be varied as desired.

It will also be understood that when desired, instead of using automatic mechanism for releasing and turning the bunch of guns, 60 such guns may be released, turned, and fired by hand without departing from some of the broad principles of the invention.

After the guns have been moved the one space the chair, actuated by springs 24 and 65 25, will be returned to its former position, and the cap 16 and rod 15 will return to their places and hold the bunch of guns to their

places. The operator will consequently only need to keep a supply of cartridges in the trough 10, they feeding by gravity automatically into the barrels. The operating drive-piston K' is arranged at its upper cylindrical end to move into and be fired out of the barrels or cannons and at its lower end to engage the rack G. After each shot or time 70 the piston is fired I recover it and push it back into the next barrel by means of coil-springs 18 of sufficient elasticity to effect such end after the propelling power of the piston has been exhausted. These springs 80 will be so adjusted as to hold the piston firmly against the charge of powder, but not of sufficient strength to resist the force of the explosion to any greater extent than is necessary to recover the piston. The piston 85 is guided by means of eyes 19 at its sides, which fit on rods 20, which rods also support the springs 18. Near its lower end the piston is provided with wheels 21, the axle 22 of which is movable along the piston, preferably by arranging it to move in a groove or slot 23 in the piston, the piston moving back from the wheels when fired; but after the propelling-power of the piston has been exhausted it will ride up on the wheels, the 90 axle of which will pass back in groove 23, so that the piston as it is dragged forward will be held above and out of engagement with the rack. The wheels 21 run upon the track-plates J, as referred to hereinbefore. The 95 cartridges may be discharged by the piston coming back against them, either by concussion or through the aid of electricity or other suitable means, and I do not desire to be limited to any particular firing mechanism. The connecting-frame L, which extends 100 between the locomotive and the car, will be built as light as possible, consistent with strength, of steel or iron base-bars 26, top bars 27, and uprights 28, all of T shape in 105 cross-section, and braced by diagonal rods 29, as shown, the parts being bolted or riveted together, as desired.

The car M is suitably connected with the connecting-frame, and consists of the casing 115 30, the guide-rods 31 therein, and the passenger-compartment 32, supported to slide back and forth on rods 31, and cushioned in both its backward and forward movements by coiled wire and rubber springs 33 and 34. 120 Within the casing 30 I secure front and rear frames 35 and 36, which support the rods 31. The casing 30 is shown as open at its rear end, the passenger-compartment being provided at its rear end with an entrance-door 37. 125

While the single piston, as shown, may be preferred, it is obvious that if desired separate pistons may be fired from each of the cannons or barrels and be permitted to fall out after each discharge, to be replaced by others.

I expect in practice to use charges of varying size and power. At first, to obtain the motion gradually, small charges of a slow-burning composition will be used. As speed

is developed larger charges of more rapidly burning composition will be used, and by frequent successive explosions the motion will be maintained.

5 Some comparatively new explosives, which produce practically neither smoke nor noise on exploding may be employed in the operation of the invention, instead of gunpowder, dynamite, and similar common explosives.

10 It will be understood that either or both the locomotive and the car may be made of paper, papier-maché, or wood, as well as or instead of iron or other metal.

Having thus described my invention, what

15 I claim as new is—

1. A rapid-transit apparatus substantially as described, comprising the track having a rack and the locomotive having a gun or cannon arranged to fire a piston against said rack, substantially as set forth.

2. In an apparatus substantially as described, the locomotive provided with a revolving group of cannons or barrels and with the movable spring-actuated operator's seat arranged to be operated by the recoil and having mechanism for locking, releasing, and turning said group of cannons arranged to be operated by the movement of the operator's seat, all substantially as and for the purposes set forth.

25 3. In an apparatus substantially as described, the carriages made in cylindro-conoidal shape, substantially as set forth.

4. In a transit apparatus substantially as described, the improved railway-track having a rack formed of a number of plates arranged at an incline and lapping one upon the other, substantially as set forth.

30 5. In a transit apparatus substantially as described, an improved railway-track having a rack formed of a number of plates arranged at an incline lapping one upon the other and provided with cushioning-plates arranged below the said rack-plates, all substantially as and for the purposes set forth.

45 6. In a transit apparatus, the combination of the rack-plates H, having between their ends flanges h, the cushions below said plates H, the stringer-beams and plates J, lapping 50 above and arranged to form stops for engagement by flanges h to limit the upward movement of the rack-plates H, all substantially as and for the purposes set forth.

7. In a transit apparatus, the improved 55 track consisting of the ties B, the side stringers C', having rails C, the center stringer D, supporting the rack-plates H and cushion-plates I, the plates H being provided with flanges h, the stringers E, the plates J, ar-

ranged to lap above the flanges h, and the connecting-bolts F and F', all substantially as and for the purposes set forth.

8. In a transit apparatus, the combination of the locomotive and car, made cylindro-conoidal in shape, the connecting-frame, the 65 cannon or gun supported by the locomotive and arranged to incline downward toward its rear or muzzle end, and a rack in the track below the gun, arranged for engagement by a piston fired from the said gun, all substantially as and for the purposes set forth.

9. The combination, in an apparatus, substantially as described, of the track having a rack consisting of plates and cushions beneath the same, the locomotive on said track 75 and provided with a cannon or gun, and a piston arranged to be fired by said gun or cannon against the rack, substantially as set forth.

10. In an apparatus substantially as described, the combination, in a locomotive, of the casing, the diaphragm-plates 5 and 6, the plates 2 and 3, supporting the cannons or guns, the breech-plate 7, having an opening for the feeding of the cartridges to the barrel, the 85 cartridge-trough, and mechanism by which the group of cannons may be turned to bring the several cannons successively to firing position, and means for locking them in said position, all substantially as and for the purposes set forth.

11. In an apparatus substantially as described, the combination of the locomotive-casing, the group of cannons supported to turn therein, the guide-rods 12 and 13, the operator's seat supported to slide on said rods, the springs 24 and 25 for actuating said seat, the devices by which to turn the cannon and to lock the same in position, and connections between the said devices and the operator's 100 chair, whereby the movement of the latter may operate such devices, substantially as set forth.

12. In an apparatus substantially as described, the combination of the locomotive-casing, the group of cannons supported to revolve in said casing, whereby they may be presented successively to firing position, a breech-plate 7, and a brace or rod 8 on the opposite side of said breech-plate from the 110 cannon and arranged in prolongation of the line of bore of the cannon in firing position, all substantially as and for the purposes set forth.
